Primary Examiner — Katrina A Betton(74) *Attorney, Agent, or Firm* — Sheridan Ross P.C.(57) **CLAIM**

The ornamental design for a rack for a vehicle, as shown and described.

DESCRIPTION

FIG. 1 is a front perspective view of the rack for a vehicle;
 FIG. 2 is a front elevation view thereof;
 FIG. 3 is a rear elevation view thereof;
 FIG. 4 is a right elevation view thereof;
 FIG. 5 is a left elevation view thereof;
 FIG. 6 is a top plan view thereof;
 FIG. 7 is a bottom plan view thereof; and,
 FIG. 8 is a perspective view of the rack for a vehicle of the embodiment of FIG. 1 provided in combination with a vehicle.
 The broken lines are included for the purpose of illustrating environment and form no part of the claimed design.
